UNITED STATES PATENT OFFICE.

FRANK MURRAY WHETSTONE, OF CHICAGO, ILLINOIS, ASSIGNOR TO MILWAUKEE CORRUGATING COMPANY, OF GREENFIELD, WISCONSIN, A CORPORATION OF WISCONSIN.

EXPANDED-METAL MACHINE.

1,353,198.

Specification of Letters Patent. Patented Sept. 21, 1920.

Application filed February 19, 1917. Serial No. 149,645.

To all whom it may concern:

Be it known that I, FRANK MURRAY WHETSTONE, a citizen of the United States, and resident of Chicago, county of Cook, 5 and State of Illinois, have invented certain new and useful Improvements in Expanded-Metal Machines, of which the following is a specification, and which are illustrated in the accompanying drawings, forming a part 10 thereof.

The invention relates to sheet metal working machines and more especially to those which are intended for producing expanded metal. One of the objects of the invention 15 is the provision of a machine which is constructed to produce expanded metal of improved quality particularly with respect to regularity in the size and shape of the meshes and to uniformity in the dimensions 20 of the strands and bonds. To this end the invention contemplates the use of slitting and forming dies of improved construction.

In the accompanying drawings:—

Figure 1 is a detail front end view of an 25 expanded metal machine embodying the features of improvement of the invention, some of the parts being shown in section and other parts being broken away to expose the slitting and forming dies,

Fig. 2 is an enlarged detail transverse sectional view taken on the plane indicated by the line 2—2 on Fig. 5, of the machine illustrated in Fig. 1 with the movable dies in a different position,

Figs. 3 and 4 are detail longitudinal sectional views taken on the planes indicated by the lines 3—3 and 4—4 respectively on Fig. 1,

Fig. 5 is an enlarged detail plan view 40 with some of the parts broken way and with the dies shown in their separated or open position,

Fig. 6 is a similar view to Fig. 5, but drawn to a still larger scale, showing the 45 dies in closed position upon the work with some of the parts broken away to expose the concealed parts at a plurality of different levels, indicated by the line 6—6 on Fig. 11,

Figs. 7, 8, 9 and 10 are enlarged detail 50 perspective views showing different elements of the machine separated from other parts, the part shown in Fig. 7 being stationary forming dies and that shown in Fig. 8 being a stationary cutter, while the 55 part shown in Fig. 9 is a spacing element

and the part shown in Fig. 10 is one of the movable cutting and expanding dies,

Fig. 11 is a detail perspective view of a partly expanded sheet with the result of a subsequent operation of the machine indicated in part by dotted lines; and

Fig. 12 is a general plan view showing the reciprocating truing bar and its actuating connections, parts of the machine being broken away.

The improvements constituting the invention are illustrated as being applied to a machine of the type shown in my patent for expanded metal machine No. 1,048,617 dated December 31, 1912. This machine op-

erates progressively upon a sheet metal strip X, beginning at one corner of the strip. A feature of the operation is that partial slits as a (Fig. 11) are first produced by the co-operation of stationary and movable slit-

ting or cutting dies, as 15—16 (Fig. 1), while each of the partial slits a is subsequently extended as at b (Fig. 11) and the strand c thus formed is deflected in a direc-

tion substantially perpendicular to the plane 80 of the original sheet X by the co-operation of a movable slitting or cutting and expanding die 17 with a stationary slitting or cutting die 18. In the improved machine

herein illustrated, the movable cutting and 85 expanding die 17 has an oblique face 19 and regularity in the shape of the meshes, as d

(Fig. 11) is insured through the fact that a part of each strand c is engaged with the oblique face 19 of the die 17 and pressed 90 against an oblique abutment shoulder 20.

While the die 17 is shown as being provided with an oblique face 19 at each end, it is to be understood that the two ends of the die are thus prepared to permit of reversing 95 the die after a period of use. Similarly, the cutting dies 15, 16 and 18 are preferably also prepared to permit of their being re-

versed when one end has been dulled by use. 100

As in the machine of my said former patent, there is a sufficient number of each of the dies 15, 16, 17 and 18 to extend in a row entirely across the sheet, as X, in oblique lines. Preferably also these rows

of dies are horizontal, the dies 17—18 being 105 located above the dies 15—16. Under these circumstances the work is fed from below and in an upwardly inclined direction, as through a feed trough 21 having an inclined bottom 22.

110

As shown, the sheet X is entered in the feed trough 21 at one end of the machine and has a step by step movement through the trough. It will therefore be observed that the work reaches the level of the dies 15, 16, before it reaches the level of the dies 17, 18. For this reason the dies 17, 18 may be omitted for a distance at one end of the machine, as at 32 (Fig. 3) and 33 (Fig. 4). However, the number of pairs of dies 17, 18 is preferably equal to the number of pairs of dies 15, 16. The rows of dies 17, 18 accordingly extend beyond the rows of dies 15, 16 at the other end of the machine.

While the rows of dies 15, 16, 17 and 18 are inclined to the path of movement of the sheet, as X, the cutting edges of all of the said dies are preferably located in planes which are parallel with the longitudinal edges of the work. For this purpose an inclined seat, as 23 or 24, is provided for each of the said dies. As shown, the inclined seats 23 for the dies 15 are formed upon or attached to and extend along a stationary head or part, as 25, of the machine frame. Similarly, the inclined seats 24 for the dies 16 are formed upon or attached to and extend along a sliding punch head, generally designated 26. The inclined seats 23 and 24 for the dies 17 and 18 are formed upon spacing blocks, as 27, (Fig. 9). These spacing blocks are applied to the said fixed part 25 of the machine frame and to the punch head 26 over the dies 15 or 16 of the corresponding lower row. The dies 16, 17 are held in place upon the punch head 26 by clamps, as 28, which bear upon the dies 17. In securing the dies 15 and 18 upon the fixed part, as 25, of the machine frame, on the other hand, provision is to be made for the location of one of the inclined abutment shoulders 20 immediately over each of the dies 18. For this purpose a former plate 29, made in sections, extends over the dies 18. The several sections of this former plate are each provided with tapering fingers or projections 30, one of which extends forwardly over each of the dies 18 and each of said fingers has an oblique outer end which serves as the corresponding abutment shoulder 20. When this arrangement is employed the dies 15 and 18, the intervening spacing blocks 27 and the sections of the former plate 29 are all held in place by the use of clamps 31 which bear upon the said former plate 29. At the places, as 32 (Fig. 3) and 33 (Fig. 4) where the dies 17 and 18 are omitted, a filling block, as 34 or 35, is introduced between the corresponding clamp 28 or 31 and the spacing block 27.

Each of the initial slits, as *a*, is formed in the work with a shearing cut by the co-operation of the lower edge of the slightly beveled front end of one of the dies 16 with

the upper edge of the square front end of the corresponding die 15. The extension, as *b*, of each slit is formed by the co-operation of the lower edge of the beveled face 19 of one of the dies 17 with the upper edge 70 of the front end of the corresponding die 18. While all of the dies, 15, 16, 17 and 18 are of uniform width, the extended portion, as *b*, of each slit is of less length than the original cut, as *a*. For this reason the 75 beveled face 19 of each die 17 does not extend the full width of the die and each of said dies has a blunt end 36 at one side. In the expansion of the work, the blunt end 36 of each die 17 engages the work at a part 80 *e*, corresponding with a bond of the expanded sheet, for deflecting the adjacent strand, as *e*, over the die 18. Similarly, as each die 18 is not required to be provided with a cutting edge throughout its full 85 width, each of said dies may be provided with a rounded corner, as 37 (Fig. 8). In order that the forward and upward movement of the slotted sheet, in front of the die 18, may not be interfered with, the forward ends of these dies are preferably beveled, as at 38.

To avoid any necessity for individual adjustment of the numerous dies, each of the dies 15, 16, 17 and 18 is desirably made of 95 uniform length with all of the other dies in the same row. Under these circumstances a single pair of stepped wedge blocks, as 39 and 40, 41 and 42, or 43 and 44, serves for adjusting all of the dies 15 100 and 18, 16 or 17 respectively. As shown, each pair of wedge blocks 39 and 40, 41 and 42 or 43 and 44, reacts between the rear ends of corresponding dies 15 and 18, 16 or 17, and an upright abutment shoulder 47 105 or 48 at the rear of the said wedge blocks, the wedge blocks 39 and 40 serving for simultaneous adjustment of both series of dies 15 and 18, while the two series of dies 16 and 17 are separately adjusted by the 110 wedge blocks 41 and 42 or 43 and 44.

The wedge blocks 39, 41 and 43 are adjusted lengthwise and are held in place by screws 45, 46 and 46' (Fig. 12.)

The punch head 26 slides upon a stationary bed plate 49 and provision is made to prevent any lifting of the punch head from the said bed plate during the engagement of the dies 16, 17, with the work. As shown, a set of T guides 50 (Fig. 3) are mounted 115 in the bed plate 49, and the punch head 26 is formed with T grooves 51, in its under side, for receiving the said T guides, which have lateral clearance therein to allow for longitudinal adjustment of the punch head. 120 The movable dies 16 and 17 are adjusted bodily with the punch head 26 lengthwise of the machine so as to properly co-operate with the stationary dies 15 and 18, by screws 26' and adjustable end guides 49' (Figs. 3 130

and 12). Movement is imparted to the punch head 26 from a drive shaft 52 (Figs. 1 and 12). As shown, this drive shaft extends at the rear of the punch head through-
 5 out the entire length of the machine and a plurality of eccentrics, as 53, (only one of which is shown) are mounted upon the said drive shaft at intervals along the same. When this construction is employed a pit-
 10 man 54 is associated with each eccentric 53, at one end, and has its other end connected with the punch head 26, as at 55.

The step by step movement of the work through the feed trough 21 is accomplished by the use of a plurality of pairs of feed rolls as 56, 57. These feed rolls are located at intervals throughout the length of the feed trough. The feed rolls of each pair engage the work upon opposite sides through
 15 notches, as 58, in the side walls of the trough. To insure uniformity both in the time and the amount of movement of the feed rolls, all of the said feed rolls are preferably actuated from a common drive shaft, as 59 (Fig.
 20 4). This drive shaft extends under the feed trough 21 and is intermittently driven, as through a pair of beveled gears 60 and 61 located at one end of the said shaft.

Accuracy in the extent of movement im-
 30 parted to the sheet, as X, at each step, is obtained by the use of a Geneva stop movement in the driving mechanism with which the said beveled gears 60, 61, are associated. As shown, the beveled gear 60 is mounted upon the front end of the feed roll drive shaft 59. The beveled gear 61 meshes with the gear 60 and is mounted on a transverse shaft 62. The transverse shaft 62 also carries the cam plate 63 of the said Geneva stop
 35 movement. The pin plate 64 of the said Geneva stop movement is located above the cam plate 63 and is mounted upon a separate transverse shaft, as 65. Preferably the two parts 63 and 64 of the Geneva stop
 40 movement are inclosed within a case, generally designated 66. The transverse shaft 65 extends through the wall of the case 66 at one side and has a universal joint connection 67 with one end of an intermediate shaft 68. The other end of the intermediate shaft 68 has a driving connection with the main drive shaft 52.

Above and parallel with the clamps 31, a vertically reciprocating truing bar 69 is guided in an auxiliary frame 70, which is horizontally hinged at one end and detachably fastened at the other end to brackets 71 and 72 on the main frame, to afford easy access to the stationary dies 15 and 18 and
 55 parts associated therewith and facilitate removing and replacing the same (Figs. 1, 2, 3 and 12).

The bar 69 is actuated by cams 73 on a shaft 74, mounted in the frame 70 and connected with the main drive shaft 52 by

beveled gears 75 and 76 and an intermediate shaft 77. The beveled gear 76 is mounted on a short transverse shaft 78 in axial alignment with the hinge connection between the frame 70 and bracket 71, and the shaft 77
 70 has universal joint connections 79 and 80 with the shaft 78 and another short transverse shaft 81, which has a gear connection with the shaft 52 inclosed by a case 82 (Fig.
 12), so that the frame 70 with the bar 69 and
 75 cam shaft 74 may be turned up out of the way without disturbing the actuating connections of said bar.

As the sheets are expanded and advanced laterally step by step over the clamps 31, 80 the inner edges of which are beveled or inclined, they are intermittently pressed by the bar 69 down upon the upper flat faces of the clamps and held in place thereon while the movable dies 16 and 17 are withdrawn clear
 85 from the slits and meshes of the sheets, said bar, the working face of which is preferably inclined slightly upward toward the feed trough 21 and overhangs the beveled or inclined faces of the clamps, as shown in Fig.
 2, operating to correct any curling, twisting, warping or winding tendency of the expanded sheet metal and leave it flat and true.

The machine has a relatively small number of moving parts and conforms readily to 95 ruggedness in design and accuracy in construction. Furthermore, its operations are uniform and positive and great regularity is obtained in the finished product. The co-operation of the oblique faces 19 of the dies 100 17 with the oblique abutment shoulders 20 of the former 29 insures regularity in the shape of the strands and the movement of the previously cut strands over the inclined upper surfaces of the fingers 30 greatly as-
 105 sists in obtaining a uniform opening of the meshes.

I claim as my invention:

1. In a machine of the kind described, in combination, two pairs of slitting dies having relative endwise movement successively engageable with the work upon contiguous areas of contact whereby slits produced by the dies of the pair first engageable with the work are extended by the dies of the other 110 pair, the dies of the pair first engageable with the work having square cutting ends and one of the dies of the other pair having an oblique cutting end whereby the dies of the pair first engageable with the work operate simultaneously at all points throughout their width and the dies of the other pair operate progressively across the same from one side of the said dies.

2. In a machine of the kind described, in combination, two pairs of slitting dies having relative endwise movement successively engageable with the work upon overlapping areas of contact, the dies of the pair first engageable with the work having square cut-
 125 130

ting ends and one of the dies of the other pair having a blunt end and a contiguous oblique cutting face whereby the work is engaged by the said blunt end of the last mentioned die at one side of the slit produced by the dies of the first separately mentioned pair and the said slit is progressively extended by the coöperation of the said oblique cutting face with the other die of the 10 same pair.

3. In a machine of the kind described, in combination, two pairs of slitting dies having relative endwise movement successively engageable with the work upon contiguous 15 areas of contact whereby slits produced by the dies of the pair first engageable with the work are extended by the dies of the other pair, the dies of the pair first engageable with the work having square cutting 20 ends, one of the dies of the other pair having an oblique cutting end for operation upon the work progressively across the said die from one side of the same, and a fixed oblique abutment located in rear of the cutting 25 end of the remaining die and against which the separated portion of the work is pressed by the die having the said oblique cutting end.

4. In a machine of the kind described, in combination, two pairs of slitting dies having relative endwise movement successively engageable with the work upon overlapping 30 areas of contact, the dies of the pair first engageable with the work having square cutting 35 ends, one of the dies of the other pair having a blunt end and a contiguous oblique cutting face whereby the work is engaged by the said blunt end of the last mentioned die at one side of the slit produced by the 40 dies of the first separately mentioned pair and the said slit is progressively extended by the coöperation of the said oblique cutting 45 face with the other die of the same pair, and a fixed oblique abutment located in rear of the cutting end of the last mentioned die and against which the separated portion of the work is pressed by the oblique face of the 50 said die having the blunt end.

5. In a machine of the kind described, in combination, two sets of dies arranged in parallel planes and successively engageable with adjoining areas of the work, means for simultaneously effecting relative endwise movement of the opposing dies, one set of dies being adapted to produce a series of non-overlapping 55 slits in stepped relation to one another, and one of each pair of opposing dies of the other set having an oblique face and cutting edge and being adapted to 60 extend the slits produced by the first set of dies and to simultaneously expand the work, and means for intermittently feeding the work between the opposing dies.

6. In a machine of the kind described, in combination, two sets of slitting dies ar-

ranged with their cutting edges in parallel planes and successively engageable with adjoining areas of the work, means for simultaneously effecting relative endwise movement of the opposing dies, one set of dies being adapted to produce a series of non-overlapping slits in stepped relation to one another, and one of each pair of opposing dies of the other set having an oblique face and cutting edge and being adapted to extend 75 slits produced by dies of the first set, an oblique abutment opposite the oblique face of each oblique faced die of the second set and adapted to coöperate therewith to form an expanded portion of the work, and means 80 for intermittently feeding and exactly positioning the work between the opposing dies.

7. In a machine of the kind described, in combination, a pair of dies in shearing relation having relative endwise movement, 85 one of the said dies being formed with a square cutting end and the other die being formed with a blunt end extending over a part only of the width of the die and with an oblique cutting face which is contiguous 90 with the said blunt end and extends throughout the remainder of the width of the die.

8. In a machine of the kind described, in combination, a pair of dies in shearing relation having relative endwise movement, one 95 of the said dies being formed with a square cutting end, the other die being formed with a blunt end extending over a part only of the width of the die and with an oblique cutting face which is contiguous with the 100 said blunt end and extends throughout the remainder of the width of the die, and an oblique abutment located in rear of the cutting end of the die having the said square end and in line with the oblique face of the 105 die having the said blunt end.

9. In a machine of the kind described, in combination, slitting and expanding dies arranged in opposing rows and capable of relative movement lengthwise toward and from 110 each other, and a pair of wedge blocks one of which is adjustable lengthwise relative to the other and transversely to the dies and adapted to simultaneously adjust lengthwise to an equal extent all the dies of a row. 115

10. In a machine of the kind described, in combination, a guide-way for the work, fixed and movable die heads arranged on opposite sides of the guide-way and provided with longitudinal shoulders, a set of slitting dies mounted in two opposing parallel rows on said heads obliquely to the movement of the work through the guide-way, a set of auxiliary slitting and expanding dies, also mounted on said heads in two 120 rows parallel with the rows of the other set, a pair of adjusting wedge blocks between the outer ends of both rows of dies of the fixed head and the shoulder thereon, and a pair of adjusting wedge blocks between the 125 130

outer ends of each row of dies of the movable head and the shoulder thereon.

11. In a machine of the kind described, in combination, a guide-way for the work, slitting and expanding dies arranged in opposing rows on opposite sides of the guide-way obliquely to the movement of the work therethrough, means for moving the dies on one side of the guide-way toward and from the opposing dies, means for intermittently feeding the work through the guide-way between the dies, and a reciprocating truing bar arranged to operate on the expanded metal.

12. In a machine of the kind described, in combination, a guide-way for the work, fixed and movable slitting and expanding dies arranged in parallel rows on opposite sides of the guide-way obliquely to the movement of the work therethrough, means for reciprocating the movable dies, means for intermittently feeding the work through the guide-way between the opposing dies, a frame hinged at one end and detachably fastened at the other end to fixed parts of the machine, a reciprocating truing bar guided in said frame opposite and parallel with a stationary part of the machine adjacent to and parallel with the row of fixed expanding dies, an actuating shaft mounted in said frame parallel with said truing bar and connected therewith, and a driving connection

with said shaft at the hinged end of said frame.

13. In a machine of the kind described, in combination, a guide-way for the work, a set of fixed and reciprocating slitting dies arranged in two rows on opposite sides of the guide-way, a set of fixed and reciprocating auxiliary slitting and expanding dies also arranged on opposite sides of the guide-way parallel with the other rows of dies to extend the slits formed by the first set of dies, and feeding mechanism for intermittently advancing the work through said guide-way predetermined intervals and locking and holding the work in exact positions for the operation of the dies thereon.

14. In a machine of the kind described in combination, two pairs of slitting dies successively engageable with the work upon overlapping areas of contact, the dies of the pair last engageable with the work having relative endwise movement and one of said dies having a blunt end and a contiguous oblique cutting face whereby the work is engaged by the said blunt end at one side of the slit produced by the dies of the pair first engageable with the work and the said slit is progressively extended by the co-operation of the said oblique cutting face with the other die of the same pair.

FRANK MURRAY WHETSTONE.
